(57) **CLAIM**

The ornamental design of a Mosfet rectifier bridge power pack, as shown and described.

DESCRIPTION

FIG. 1 is a perspective view of a Mosfet rectifier bridge power pack showing our new design;

FIG. 2 is a top plan view thereof;

FIG. 3 is a first side elevation view thereof;

FIG. 4 is a second side elevation view thereof;

FIG. 5 is a third side elevation view thereof;

FIG. 6 is a bottom plan view thereof; and,

FIG. 7 is a fourth side elevation view thereof.
